Inventor,
Samuel Silvers, by
G. C. Kennedy,
Attorney.

UNITED STATES PATENT OFFICE.

SAMUEL SILVERS, OF WATERLOO, IOWA.

DELIVERY DEVICE FOR LIQUID DISINFECTANTS.

1,366,426.

Specification of Letters Patent. Patented Jan. 25, 1921.

Application filed May 6, 1920. Serial No. 379,401.

To all whom it may concern:

Be it known that I, SAMUEL SILVERS, a citizen of the United States of America, and a resident of Waterloo, Blackhawk county, 5 Iowa, have invented certain new and useful Improvements in Delivery Devices for Liquid Disinfectants, of which the following is a specification.

My invention relates to improvements in 10 delivery devices for liquid disinfectants, and the object of my improvement is to supply a device of this class for use in a water-closet having a swinging seat; and operated to deliver a liquid disinfectant when the 15 seat is swung down and away from its normally raised position.

This object has been accomplished by the means which are hereinafter described and claimed, and which are illustrated in the accompanying drawings, in which Figure 1 is a perspective view of a closet having a swinging seat which is normally kept in a raised position by the gravity of the disinfectant holding and delivering device attached thereto; Fig. 2 is a medial vertical longitudinal section of the same, and Fig. 3 is a perspective view of the seat and attached devices as separated from the closet-bowl, the seat being shown in section.

30 In said views, similar numerals of reference denote similar parts.

I have shown a stoneware suction jet water-closet bowl 1 of a well known type, but the device of my invention is suitable for use on any kind of closet bowl. The 35 numeral 2 denotes a light but rigid orificed seat to be hingedly mounted at one end on the rear part of the bowl to swing up and down. The rear part of the seat is scrolled 40 and the scrolls are fixedly mounted on a transverse pintle-rod 5 so that the seat and rod may rock back and forth together as said rod is seated to rock in an intermediate scroll 3 on a plate 4 fixedly secured to the 45 top of the rear part of the bowl. 6 is a sleeve fixedly and removably secured on an end of the rod 5 by means of a set-screw, and said sleeve has an integral oppositely disposed sleeve-member 7 which is removably and fixedly mounted on a hollow cylindrical spout 8 by means of a set-screw. The

forward end of the spout extends under and in contact with one side of the under surface of the downwardly concaved seat 2, and the forward extremity of the spout is 55 bent downwardly. The other end of the spout traverses and is secured in an opening in a screw-cap 9 mounted on a hollow vessel 10. A short angular air-relief tube 11 also 60 traverses and is fixed in said screw cap, as shown in Fig. 2. It will be seen that when the vessel 10 is filled with a liquid disinfectant or other liquid preparation, it will ordinarily, be heavy enough to overbalance the seat 2 and the forward part of the spout 65 8 so as to keep the seat normally raised, as shown in said Fig. 1. In this position, as the spout 8 is directed upwardly, none of the liquid can escape from the vessel 10. Only when the seat 2 has been lowered to the position shown in Fig. 2, will a portion of the liquid in said vessel 10 be delivered through the spout 8 into the contents of the bowl 1.

The vessel 10 should be made with thick, heavy walls so that even when empty, its 70 weight, alone, will similarly overbalance the seat 2 to keep it in its raised position. In case the vessel 10 is supplied in the shape of a ready filled metal can of light weight, it is obvious that some weight or heavy 75 body may be removably secured thereon to provide the proper gravity.

Either one or two vessels 10 may be mounted on the rod 5, and in Fig. 1, two of them are shown so mounted on the rod on 80 opposite sides of the bowl, which thus equalizes the action thereof on the seat.

Having described my invention, what I claim as new, and desire to secure by Letters Patent, is:

1. In combination, an open top receptacle, an orificed seat pivotally mounted at one end to swing toward and from said receptacle, and a counterweight heavier than and connected to said seat at the opposite 95 side of said pivotal connection, said counterweight comprising a hollow closed vessel and a spout extending therefrom past said pivotal connection to deliver into said receptacle when the seat is in its lower position.

2. In combination, an open top receptacle,

an orificed seat positioned thereover and hinged at one end thereto to swing upwardly therefrom, an arm extending from said seat laterally, a hollow closed body heavier than said seat, positioned beyond said hinge opposite said seat and arm, and a spout on said body removably secured to said arm and ex-

tending therebeyond under said seat to deliver into said receptacle when the seat is lowered toward the latter.

Signed at Waterloo, Iowa, this 7th day of April, 1920.

SAMUEL SILVERS.
